LAPPING BLOCK

Knut Robert Sjogren, Los Angeles, Calif.

Application March 21, 1944, Serial No. 527,383

1 Claim. (Cl. 51—212)

My invention relates to a lapping block, and more specifically to one for lapping the points of a micrometer to square the same.

I have found that a micrometer can be lapped to squareness only by the use of a lapping block having three or more surfaces of different widths. If less than three sizes of lapping blocks are used, it is impossible to get true squareness on the micrometer points. The use of one or two permits the micrometer to be ground so that the points are perfectly parallel to each other, but they will not become parallel and perpendicular to their axis except by the use of three blocks.

An object of my invention is to provide a lapping block to have three or more lapping surfaces to lap the points of a micrometer into true squareness.

Another object of my invention is to provide a lapping block which contains its own abrasive compound.

Another object of my invention is to provide a lapping block which can be cheaply and easily manufactured and easily used.

Other objects and advantages of my invention will be apparent from the following description of the preferred embodiments thereof.

In the drawing:

Fig. 1 is a plan view.

Fig. 2 is a side view partially in section.

Fig. 3 is a bottom view.

A lapping block constructed in accordance with my invention, comprises a body 1 which has a top surface 2 which is parallel to the bottom surfaces 3, 4, and 5. On the surface 2 is cut grooves 6 for the reception of a lapping compound such as powdered carborundum. The surfaces 3, 4, and 5 are all parallel to the surface 2, and each surface progressively further apart from the surface 2. One rotation of a micrometer causes the points thereof to move .025 of an inch. I therefore form the surface 3 at any given spacing from the surface 2. The distance between the surface 2 and the surface 4 is made substantially one-

third of .025 of an inch greater than the distance between the surface 2 and the surface 3. Similarly, the distance between surface 2 and surface 5 is one-third of .025 of an inch greater than the distance between surface 2 and surface 4. While I have adapted the steps on one-third of one rotation of the micrometer, two-thirds of a rotation or similar spacing would be usable.

In the use of my lapping block, a projection 7 is inserted in a vise with the face 2 facing upward. Upon the surface 2 is placed the usual lapping compound comprised of carborundum. The micrometer points 10 and 11 are then positioned upon the surfaces 2 and 3 respectively, and the same lapped until they are smooth. The micrometer is then opened one-third of a turn, which enables the same to then be slid up onto the surfaces 2 and 4 where it is again lapped until smooth. The micrometer is then opened another one-third of a turn, and again lapped between the surfaces 2 and 5. Upon completion of this last lapping, the micrometer points will be actually parallel and the surfaces thereof perpendicular to the shaft of the points.

25 To provide an easy place to contain the lapping compound, I form the bore 12 in the center of the body 1, and have a cap 13 therefor. Into this bore 12 can be placed any desired lapping compound.

30 The body 1 can be made of any thickness for use upon any size micrometer.

While I have described the preferred embodiments of my invention, I am not limited to any details therein set forth, except as described in the following claim.

35 I claim:

In a lapping block, a body having an upper surface and a lower surface parallel thereto, said lower surface being divided into three or more steps, said steps being progressively .0083 inch higher.

KNUT ROBERT SJOGREN.
